Primary Examiner — Paula Allen Greene(74) *Attorney, Agent, or Firm* — WCF IP(57) **CLAIM**

The ornamental design for a headset with microphone boom, as shown and described.

DESCRIPTION

FIG. 1 is a perspective view of a headset with microphone boom showing the new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof; and,

FIG. 8 is a perspective view of a headset with microphone boom in an alternate position thereof.
